UNITED STATES PATENT OFFICE.

JOHN W. EVANS, OF WEYERS CAVE, VIRGINIA.

SOUND-BOX RAISING AND LOWERING ATTACHMENT FOR PHONOGRAHS.

1,362,859.

Specification of Letters Patent. Patented Dec. 21, 1920.

Application filed April 3, 1920. Serial No. 371,074.

To all whom it may concern:

Be it known that I, JOHN W. EVANS, a citizen of the United States, residing at Weyers Cave, in the county of Augusta and State of Virginia, have invented certain new and useful Improvements in Sound-Box Raising and Lowering Attachments for Phonographs, of which the following is a specification, reference being had to the accompanying drawings.

This invention relates to phonographs, and particularly to the tone arms and sound boxes thereof.

It is necessary to lower the sound box in order to bring the stylus into engagement with the record or raise the sound box in order to carry the stylus out of engagement with the record.

At the present time this is accomplished by shifting the gooseneck which carries the sound box, and in order to carry the stylus away from the record it is necessary to turn the gooseneck almost completely over until the gooseneck rests upon the tone arm or upon a bracket carried by the tone arm, and when it is desired to play the record, the gooseneck must be reversely shifted through a relatively great angular distance until the stylus rests upon the record.

Aside from the relatively great extent of movement involved in the above operation and the amount of work which must be accomplished each time that a record is changed, this operation is objectionable for a number of reasons. For instance, the shadow of the hand used in rotating the sound box and gooseneck tends to prevent the stylus from being seen and thus prevents the stylus from being lowered accurately into engagement with the record groove. Oftentimes the stylus is thus lowered on the margin of the record instead of in the record groove, thus scratching the record and injuring the stylus. Furthermore,

more, rings on the fingers of the operator or buttons on his coat tend to scratch the record while the sound box is being raised or lowered.

My invention, hereinafter specifically described, is designed especially for use in connection with what is known as the tungstone stylus, and it is well known that a great

many persons object to the use of this type of stylus, claiming that the sound box is liable to be lowered too quickly or unsteadily by nervous persons, whereby the stylus will dig into the record groove and whereby the point of the needle is liable to be injured by a too sudden or too hard contact with the record.

With these and other objections in mind, the object of my invention is to provide means whereby the sound box and free end of the gooseneck may be raised or lowered to a requisite extent to lift the stylus from the record or bring the stylus into engagement with the record without the necessity of the operator taking hold of the sound box or gooseneck and rotating the gooseneck as described.

And a further object is to provide means whereby the sound box need only be raised or lowered through a relatively short distance and may be lowered gently onto the record.

Still another object is to provide means whereby not only the sound box may be raised from the record tablet, but whereby the sound box may be supported in its raised position as long as desired.

Still another object is to provide a device of this character in the nature of an attachment which may be readily applied to the knuckle at the connection of the gooseneck with the tone arm.

And a further object is to provide a device of this character so constructed that the degree to which the tone arm and sound box may be lowered may be adjusted.

Other objects will appear in the course of the following description.

My invention is illustrated in the accompanying drawings, wherein:

Figure 1 is a perspective view of a tone arm and gooseneck showing my attachment applied thereto and showing the sound box in dotted lines;

Fig. 2 is a fragmentary side elevation of the tone arm and gooseneck of my device;

Fig. 3 is a perspective view of the clip;

Fig. 4 is a top plan view of the blank from which the clip is made;

Referring to these drawings, and particularly to Fig. 1, it will be seen that my de-

vice comprises a clip 10 formed of a sheet metal blank bent to partially embrace the knuckle of the tone arm A, through which knuckle the gooseneck B passes in the usual manner, this clip 10 having one of its longitudinal edges 11 cut out, as at 12, to fit around the tapered extremity of the tone arm so as to hold the clip when it is in place from longitudinal movement. The material from which this clip is made is somewhat resilient so that the clip may be easily slipped into place on the knuckle or head at the extremity of the tone arm and then will contract and hold. Of course, the opposite longitudinal edge 13 of this clip bears against the under face of the body of the tone arm, as shown most clearly in Fig. 2, thus preventing any rotation of the clip upon the knuckle which it embraces.

The clip 10 is formed at one end with a laterally projecting arm 14 which is bent to extend forward, as at 15. The opposite end of the clip is formed with a laterally extending arm 16 which is forwardly bent, as at 17. These arms rotatably support a shaft 18, one extremity of which shaft is provided with an operating handle, as for instance, the crank shaft handle 19, and the opposite end of the shaft is provided with a crank 20 which is relatively long and extends beneath the gooseneck B, as illustrated most clearly in Fig. 1. It will be noticed that the cranks 19 and 20 are not disposed exactly in alinement with each other, and that the shaft 18 extends parallel to the rotative axis of the gooseneck B.

Upon a rotation of the shaft 18 by means of the crank handle 19, it will be obvious that the crank 20, if the shaft 18 be rotated in one direction, will lift the gooseneck B, and if it be rotated in the other direction, will lower the gooseneck B. In order to hold the shaft 18 in one of its two positions, I provide on the arm 14 the stop 21 upon which the crank handle 19 will strike when the crank handle is turned to the dotted line position shown in Fig. 2, that is when the gooseneck is raised. I have shown this stop 21 as being struck out from the body of the arm 15, but I do not wish to be limited to this.

In order to support the crank 20 in its lowered position, I provide on the arm 17 the stop 22 which is shown as being formed of a lug integral with the arm 17 bent out at right angles to the plane of the arm and being separated for a portion of its depth from the body of the arm by means of a slit 23. This stop 22 will engage the outwardly projecting arm of the crank 20 and limit the downward movement of this crank 20. The purpose of forming the slit 23 between the forward edge of the stop 22 and the body of the arm is to permit the forward edge of the stop to be adjusted by means of

pliers to thereby adjust the extent to which the crank 20 may be lowered before engaging the edge of the stop.

As before stated, I do not wish to be limited to the particular construction which I have illustrated, as my invention might be embodied in many different forms without departing from the spirit thereof, so as to make the attachment applicable to the different types of machines for which it is intended. Preferably, however, the clip 10 will be constructed from a rectangular blank, such as shown in Fig. 4, this blank being provided with the integral arms 14 and 16 stamped out with the blank, the perforations 80 for the shaft 18 being stamped out in these arms, and the arms being stamped out respectively to provide the stops 21 and 22.

In the practical use of this device, when it is desired to lift the stylus from the record tablet, the crank handle 19 is rotated from the full line position in Fig. 2 to the dotted line position thereof, thus lifting the gooseneck to the dotted line position and, of course, lifting the stylus with it off the record. Under these circumstances, the crank arm 20 has passed its center when the crank handle 19 is disposed against the stop 21 and, therefore, the weight of the gooseneck and the sound box will prevent any accidental reverse movement of the shaft 18 and the sound box will be held raised. When it is desired to lower the sound box, the crank handle 19 is oscillated in a reverse direction to carry the crank arm 20 to the position shown in full lines in Fig. 2 and until this crank arm strikes the stop 22, which will bring the stylus into operative engagement with the record.

Inasmuch as the free end of the gooseneck has but a relatively short distance to move from a raised to its depressed position, or vice versa, it is obvious that even if the operator's finger should slip off the handle 19 and the sound box should fall, the distance of fall is too slight for the stylus to be much damaged or for the record to be damaged to any extent. However, there is very little likelihood of the operator's fingers slipping from the handle 19, and inasmuch as there is a relatively large amount of motion of the handle 19 for a very small movement of the gooseneck, it follows that the sound box will be lowered gently so as to bring the stylus gently into contact with the record groove without any danger of injuring the groove or injuring the stylus. Furthermore, inasmuch as the hand of the operator is applied merely to the crank handle 19, it is obvious that there will be no shadow cast on the stylus itself and the operator can see exactly where the stylus is going. Furthermore, the provision of the stop 22, limiting the downward movement of the sound box and, therefore, the downward

movement of the stylus, prevents the stylus from dropping onto the wood of the cabinet, which is a more or less common occurrence where the gooseneck has to be rotated 5 through nearly a half circle in order to carry the sound box into or out of operative position.

While I have illustrated a crank handle 19 as being the means whereby the shaft is 10 rotated, I do not wish to be limited to the use of the crank handle, as it is obvious that the handle could be formed in other ways. Neither is it necessary that the handle should project radially in nearly the same 15 direction as the crank arm 20, as the crank handle might be extended in other radial directions.

While I have illustrated my device in the form of an attachment, this being the preferable form of my invention, yet I do not 20 wish to be limited thereto, as it is obvious that the device might be made as part of the tone arm or knuckle thereof, if desired.

I claim:—

25 1. The combination with the tone arm of a phonograph, and a gooseneck rotatably mounted at one end in said tone arm, of means carried by the tone arm whereby the free end of the gooseneck may be raised or 30 lowered and including a shaft extending parallel to the rotative axis of the gooseneck but eccentric thereto and having a handle at one end and having a crank arm at the opposite end extending beneath the gooseneck, 35 an oscillation of the shaft in one direction raising the gooseneck and an oscillation of the shaft in the other direction lowering the gooseneck.

2. The combination with the tone arm of a phonograph, and a gooseneck rotatably mounted at one end in said tone arm, of means carried by the tone arm whereby the free end of the gooseneck may be raised or 40 lowered and including a shaft extending parallel to the rotative axis of the gooseneck but eccentric thereto and having a handle at one end and having a crank arm at the opposite end extending beneath the gooseneck, 45 an oscillation of the shaft in one direction raising the gooseneck and an oscillation of the shaft in the other direction lowering the gooseneck, and stops limiting the range of 50 oscillation of the shaft.

3. The combination with the tone arm of a phonograph, and a gooseneck rotatably mounted at one end in said tone arm, of means carried by the tone arm whereby the free end of the gooseneck may be raised or 55 lowered and including a shaft extending parallel to the rotative axis of the gooseneck but eccentric thereto and having a handle at one end and having a crank arm at the opposite end extending beneath the gooseneck, 60 an oscillation of the shaft in one direction raising the gooseneck and an oscil-

lation of the shaft in the other direction lowering the gooseneck, and stops, one limiting the downward movement of the crank arm on the shaft to thereby limit the extent of depression of the free end of the gooseneck, and the other limiting the oscillation of the shaft in the opposite direction to a position where the crank arm has passed a vertical plane extending through the axis of rotation of the shaft. 70 75

4. The combination with the tone arm of a phonograph and a gooseneck rotatably engaged therewith for oscillation in a vertical plane, of means for vertically moving the free end of the gooseneck comprising a shaft 80 operatively supported upon the tone arm and extending parallel to the rotative axis of the gooseneck but eccentric thereto, said shaft at one end having a crank-shaped handle and at its opposite end having a 85 crank arm extending beneath the gooseneck, and stops engaging with said crank arm and handle respectively to limit the rotation of the shaft in either direction.

5. The combination with the tone arm of 90 a phonograph and a gooseneck swingingly connected thereto for vertical movement, of means for raising or lowering the free end of the gooseneck comprising arms projecting outward from the head of the tone arm at 95 right angles to the rotative axis of the gooseneck, a shaft passing through said arms, one end of the shaft being formed to provide a handle, the opposite end of the shaft being formed with a crank arm extending beneath 100 the gooseneck, one of said first named arms being formed with a stop limiting the rotation of the shaft to a position where the crank arm has moved upward past a vertical plane extending through the axis of rotation of the shaft, and a stop on the opposite one of the first named arms limiting the downward movement of the crank arm. 105

6. An attachment for the tone arms of phonographs comprising a clip adapted to 110 embrace the knuckle or head of a tone arm and extend concentrically to the rotative axis of the knuckle, supporting arms extending from said clip at right angles to the axis of the clip, a shaft rotatably mounted in 115 the ends of said supporting arms, one end of the shaft being formed to provide a handle and the opposite end being cranked and laterally projecting to extend beneath the tone arm of the phonograph and means for 120 limiting the rotation of said shaft.

7. An attachment for the tone arms of phonographs comprising a clip adapted to 125 embrace the knuckle or head of a tone arm and extend concentrically to the rotative axis of the knuckle, supporting arms extending from said clip at right angles to the axis of the clip, a shaft rotatably mounted in the ends of said supporting arms, one end of the shaft being formed to provide a 130

- handle and the opposite end being cranked and laterally projecting to extend beneath the tone arm of the phonograph.
8. An attachment for the tone arms of phonographs comprising a clip adapted to embrace the knuckle or head of a tone arm and extend concentrically to the rotative axis of the knuckle, supporting arms extending from said clip at right angles to the axis 10 of the clip, a crank handle formed at one extremity of said shaft whereby the shaft may be oscillated, a crank arm formed at the opposite extremity of said shaft and laterally extended to extend beneath the goose-neck of the phonograph, a stop carried by one of said supporting arms and engaging the crank handle and limiting the rotation of the shaft in one direction to a position where the crank arm has passed a vertical 15 plane extending through the axis of rotation of the shaft, and a stop on the opposite supporting arm engaging with said crank arm
- 15
- 20

to limit the downward movement of said crank arm on an oscillation of the shaft in the opposite direction.

9. An attachment of the character described comprising a clip formed of a rectangular sheet of metal and bent to embrace the knuckle or head of a tone arm and formed to engage with the body of the tone 25 arm to prevent longitudinal movement of the clip thereon, said clip being provided with outwardly projecting supporting arms, a shaft passing through the supporting arms formed at one end with a crank handle 30 whereby the shaft may be oscillated and at the other end with a crank arm to extend beneath the gooseneck of a phonograph, the supporting arms being formed with stops 35 limiting the oscillation of said shaft.

In testimony whereof I hereunto affix my signature.

JOHN W. EVANS.
